UNITED STATES PATENT OFFICE

VANCE C. PALMER, OF SIOUX CITY, IOWA

DESIGN FOR A CHILD'S DRESSING CHAIR

Application filed March 30, 1932. Serial No. 43,329. Term of patent 7 years.

To all whom it may concern:

Be it known that I, VANCE C. PALMER, a citizen of the United States, residing at Sioux City, in the county of Woodbury and State of Iowa, have invented a certain new, original, and ornamental Design for a Child's Dressing Chair, of which the following is a specification, reference being had to the accompanying drawings, forming a part thereof, in which—

Fig. 1 is a side elevation of the dressing chair showing my new design, and
Fig. 2 is an end elevation of the same.

I claim:
The ornamental design for a child's dressing chair, as shown.

VANCE C. PALMER.
